FURNITURE PANEL OR THE LIKE

Howard E. Patron, West Islip, N.Y., assignor to The Thomas Holmes Corporation, Jenkintown, Pa.

Filed Nov. 8, 1971, Ser. No. 196,879

Term of patent 14 years

Int. Cl. D6—06

U.S. Cl. D6—192

FIG. 1

FIG. 2

FIG. 6

FIG. 3

FIG. 5

FIG. 4

FIG. 1 is a front elevational view of a furniture panel or the like showing my new design;

FIG. 2 is a side elevational view;

FIG. 3 is a plan view;

FIG. 4 is a rear elevational view at greatly reduced scale;

FIG. 5 is a sectional view taken along line 5—5 of FIG. 1; and

FIG. 6 is a sectional view taken along line 6—6 of FIG. 1.

I claim:

The ornamental design for a furniture panel or the like, substantially as shown and described.
